GUIDE FOR DRILL CHUCKS

Herbert J. Willmott, Beverly, Mass., assignor to
United Shoe Machinery Corporation, Flemington, N. J., a corporation of New Jersey

Original application August 4, 1943, Serial No. 497,415. Divided and this application December 21, 1944, Serial No. 569,122

7 Claims. (Cl. 144—92)

1

This invention relates to means by which chucks for holding drills are guided for movement along predetermined paths, it being particularly concerned with the accurate maintenance of such paths.

In the application for Letters Patent filed in my name in the United States Patent Office on August 4, 1943, and bearing the Serial No. 497,415, of which the present case is a division, there is disclosed a machine in which a plurality of drills act simultaneously upon a shoe-heel. This is to form through the heel-seat-end a group of passages arranged in accordance with a drilling design, which corresponds to a group of nails inserted in the heel-seat of a shoe. These nails are to enter the heel-passages to effect the attachment of the heel. Obviously, there must be exact agreement between the arrangement of heel-passages and the inserted nails to permit such assembly. For different sizes of heels, these designs differ, and in the above-mentioned machine the drilling mechanism is so organized that by a single movement of adjustment all the drills of the gang may be shifted into positions for any of the possible designs. It is a purpose of this invention to ensure that the drill-holding chucks, in their movement of adjustment, shall be so guided that the correct designs are attained. To this end, I provide a drill-mounting in which is one or more depressions, each furnishing a guideway and having two walls substantially at right angles to each other. In contact with one of the walls, a drill-chuck-carrier is movable with the axis of the drill parallel to said wall. In the chuck-carrier is a groove extending transversely of the axis of the drill, and along the second depression-wall a guide member is movable, it lying in the carrier-groove. In this second wall, means is movable for forcing the guide member into the carrier-groove. These two mounting surfaces may be machined accurately, so their relation to the mounting and to each other is definitely established, as is also the effect of the forcing or adjusting means upon the guide member and carrier. The adjusting means may consist of a single screw threaded into the second depression-wall, with its axis substantially parallel to the first depression-wall. Preferably, the guide member has two inclined surfaces entering and complementary to surfaces of a V-groove in the chuck-carrier. It also has a third surface inclined with respect to the guideway-wall along which the chuck-carrier is movable, this third surface receiving contact of a complementary inclined surface on the adjusting screw. After the guide member has been

2

brought by this screw-surface into correct engagement with the carrier, and said carrier with the depression-wall, they may be there retained by means shown as consisting of a plate extending along the guide member and forced against it by screws threaded into the mounting. Locking means is provided for the adjusting screw. This may consist of a peripheral inclined surface on the screw and a plate having a surface complementary thereto, these surfaces being forced into locking engagement. The previously mentioned application matured into Patent No. 2,379,844 on July 10, 1945.

In the accompanying drawing illustrating a particular embodiment of the invention,

Fig. 1 is an enlarged front elevation of the drilling mechanism, with the means for varying the drilling design;

Fig. 2, an enlarged longitudinal sectional detail through one of the drill-chucks;

Fig. 3, an enlarged sectional detail of the chuck-guiding and retaining means on the line III—III of Fig. 1;

Fig. 4, a rear elevation of said guiding and retaining means; and

Fig. 5, an enlarged sectional detail on the line V—V of Fig. 1.

Upon spaced horizontal rods 50, 50 furnishing a portion of the frame of a drilling machine, a main slide 54 is movable under the power of the machine. Upon this slide a second slide 92 is variable in position longitudinally to alter the depth of drilling. Fixed to the adjusting slide is a mounting head 56. In a depression 150 in the rear face of the upper portion of the mounting is secured a carrier 152 for one of a plurality of chucks K for drills 58, this carrier 152 corresponding to the rear nail of a group inserted in the heel-seat of a shoe. Four carriers 154 are guided in radiating or outwardly diverging depressions 156 in the mounting, and at the inner extremity of each of the carriers 152 and 154 is a horizontal bore 158 to receive a driven chuck-shaft 160. Each chuck-shaft is rotatable in flanged bushings 202 fitting the opposite ends of the bore 158, and has threaded upon its forward extremity a flanged sleeve 204. This forces back into a conical depression in the shaft a collet 206, which clamps in place one of the drills 58. Each of the carriers 154 has near its outer extremity a rearward projection 162 entering a cam-slot 164 in a circular plate 166, rotatable in a recess at the rear of the mounting and retained in place by a cover 168. The plate has an upwardly extending arm or hand-hold 170, through which it may be turned by the operator.

A latch 172 upon the arm enters any one of a series of notches 174 in a segment 176 attached to the top of the mounting 56 to fix the plate in a plurality of angular positions corresponding to different drilling and inserting designs, indicated by designations 178 associated with the segment-notches.

To guide each of the carriers 154 accurately in their movement of adjustment along the depressions 156 by the cam-plate 166, each of these depressions has a longitudinal wall with a finished surface *a* extending along a plane parallel to the axis of the corresponding drill, in the direction in which said drill is to move in its action upon the heel. At one side of each depression is an extension 181 of less length than the main depression, and having at its forward extremity a wall upon which is a finished surface *b* at right angles to the surface *a* and to the axis of the drill. With each mounting-surface *a* contacts a finished surface *c* upon one of the carriers 154, this lying parallel to the axis of its drill. Between all other portions of the carrier and the mounting there is clearance space. At the side of the carrier opposite the surface *c* is a longitudinal V-groove 180 extending transversely of the axis of the drill. Lying in this groove is an elongated guide member 182, having side walls *d* complementary to and contacting with the walls of the groove. A surface *e* of the guide member is movable in contact with the mounting-surface *b* toward and from the mounting-surface *a*. This movement is effected and maintained to hold the carrier-surface *c* at all times in close sliding contact with the mounting-surface *a*, by a generally cylindrical adjusting screw 188, lying in the depression-extension 181 with its end threaded into the wall *b* of the mounting. The adjusting member 188 has adjacent to the threaded end an inclined peripheral surface 190, engaging a complementary surface 192 upon the guide member. It is provided with a slotted head 194, through which it may be rotated to urge the surface 190 against the surface 192 of the guide member. Moving along the carrier-surface *b*, the guide member forces the carrier-surface *c* into accurate engagement, throughout its length, with the mounting-surface *a*, keeping the carrier away from all other mounting-surfaces. Therefore, as the carrier is positioned by the cam-slot 164 in the plate 166 along the depression 156 for different drilling designs, the path in which it is moving will be accurately maintained by the bearing furnished by the mounting-surface *a* and the guide-surfaces *d*, *d*. Wear may readily be taken up by the adjusting screw 188 without disturbing the path in which the drill is to move, and new carriers may be supplied for those which are worn or broken, with no other fitting or adjustment than is furnished by manipulation of the member 188.

To hold the guide member 182 in its adjusted relation, a cover-plate 184 extends along it in contact with a surface *f* opposite the surface *e*. The cover-plate is urged into clamping relation to the guide member by screws 186, 186, which extend with some clearance through openings in said guide member and are threaded into the mounting. The adjusting member 188 lies in a clearance-opening in the cover-plate. To secure this member against rotation as adjusted, a locking plate 196 has an opening with a conical wall 198, which contacts with a complementally inclined periphery on the head 194 of the member. The locking plate 196 is attached to the cover-

plate 184 and forced into its locking relation, by a screw 200 threaded into the cover-plate with its head bearing against the locking plate.

In taking up wear in any one of the adjustable 5 chuck-carriers 154, it is only necessary to remove the plates 166 and 168 of the mounting, this giving access to all the chuck-carriers with their guides and associated elements. Backing off the screws 200 and 186 to release the adjusting screw 188 and the retaining plate 184, said adjusting screw is rotated to force its inclined surface 190 against the surface 192 of the guide member 182. This urges the surfaces *d*, *d* of the guide member into contact with the carrier-surfaces 180, 180, and, consequently, the surface *c* of the carrier against the surface *a* of the mounting, without affecting the position of the carrier longitudinally of the drill contained in the carrier-chuck. There is thus determined a path parallel to the drill-axis along which the carrier may be adjusted by the action of the cam-slot 164. The screws 186 and 200 are then tightened to clamp the guiding and adjusting elements in place. If a chuck-carrier is to be replaced, the plate 196 and screw 25 188 are removed, and then the plate 184 and guide 182. This frees the carrier, which is taken out, another substituted, and the associated elements returned in the reverse order. It is to be observed that the chuck-carrier-guiding means, 30 with the adjusting and securing elements, are contained compactly within the depression in the mounting, yet all are readily accessible.

Having described my invention, what I claim as new and desire to secure by Letters Patent of 35 the United States is:

1. In a drilling machine, a mounting in which is a depression having two walls substantially at right angles to each other, a drill-chuck-carrier movable in contact with one of the depression-walls with the axis of the drill parallel to said wall, said carrier having a groove extending transversely of the axis of the drill, a guide member movable along the second depression-wall toward the first-mentioned wall and lying in the groove 40 in the carrier, and means movable in said second depression-wall for forcing the guide member into the carrier-groove against opposite walls thereof.

2. In a drilling machine, a mounting in which is a depression having two walls substantially at right angles to each other, a drill-chuck-carrier movable in contact with one of the depression-walls with the axis of the drill parallel to said wall, said carrier having a groove extending transversely of the axis of the drill, a guide member 45 movable along the second depression-wall and lying in the groove in the carrier, and a screw threaded into the second depression-wall with its axis substantially parallel to the first depression-wall and engaging the guide member to force it toward said first depression-wall.

3. In a drilling machine, a mounting in which is a depression having two walls substantially at right angles to each other, a drill-chuck-carrier movable in contact with one of the depression-walls with the axis of the drill parallel to said wall, said carrier having a groove extending transversely of the axis of the drill, a guide member movable along the second depression-wall and lying in the groove in the carrier, means movable in said second depression-wall for forcing the guide member into the carrier-groove, means for retaining the guide member in the position to which it may be forced, and means movable into engagement with the forcing means for

locking said forcing means in the position to which it may be moved.

4. In a drilling machine, a mounting having a guideway, a drill-chuck-carrier movable along the guideway in contact with one of the walls thereof and provided with a V-groove extending transversely of the axis of the drill, a guide member movable upon the mounting at the opposite side of the chuck-carrier from the guideway-wall and having two inclined surfaces complementary to and contacting with those of the groove and with a third surface inclined to the guideway-wall, and a guide-adjusting screw threaded into the mounting and having an inclined surface complementary to and engaging the third inclined surface of the guide member.

5. In a drilling machine, a mounting having a guideway, a drill-chuck-carrier movable along the guideway in contact with one of the walls thereof and provided with a V-groove extending transversely of the axis of the drill, a guide member movable upon the mounting at the opposite side of the chuck-carrier from the guideway-wall and having two inclined surfaces complementary to and contacting with those of the groove and with a third surface inclined to the guideway-wall, a guide-adjusting screw threaded into the mounting and having an inclined surface complementary to and engaging the third inclined surface of the guide member, a plate extending along the guide member, and screws threaded into the mounting and by which the plate may be forced into retaining engagement with the guide member.

6. In a drilling machine, a mounting having a guideway, a drill-chuck-carrier movable along the guideway in contact with one of the walls thereof and provided with a V-groove extending transversely of the axis of the drill, a guide member movable upon the mounting at the opposite side of the chuck-carrier from the guideway-wall and having two inclined surfaces complementary to and contacting with those of the groove and with a third surface inclined to the guideway-wall,

10 a guide-adjusting screw threaded into the mounting, said screw having an inclined surface complementary to and engaging the third inclined surface of the guide member and having a peripheral inclined surface, a plate extending along the guide member, screws threaded into the mounting and by which the plate may be forced into retaining engagement with the guide member, a locking plate for the adjusting screw provided with a surface complementary to the peripheral inclined surface, and a screw threaded into the retaining plate and by which the inclined surfaces of the locking plate and guide-adjusting screw may be forced into engagement.

Certificate of Correction

Patent No. 2,450,066.

September 28, 1948.

HERBERT J. WILLMOTT

It is hereby certified that error appears in the printed specification of the above numbered patent requiring correction as follows:

Column 2, line 12, for the patent number "2,379,844" read *2,379,944*;
and that the said Letters Patent should be read with this correction therein that the same may conform to the record of the case in the Patent Office.

Signed and sealed this 5th day of April, A. D. 1949.

[SEAL]

THOMAS F. MURPHY,
Assistant Commissioner of Patents.
